COMBINED SILENT BUTLER AND CRUMBER

Louis Farber, Bronxville, N. Y.

Application March 16, 1954, Serial No. 29,561

Term of patent 14 years

(Cl. D85—2)

To all whom it may concern:

Be it known that I, Louis Farber, a citizen of the United States, residing at Bronxville, county of Westchester, State of New York, have invented a new, original, and ornamental Design for a Combined Silent Butler and Crumber, of which the following is a specification, reference being had to the accompanying drawing, forming a part thereof.

Fig. 1 is a top plan view of a combined silent butler and crumber showing my new design;

Fig. 2 is a side elevational view thereof; and
Fig. 3 is a front elevational view thereof.

I claim:

The ornamental design of a combined silent butler and crumber, substantially as shown.
